UNITED STATES PATENT OFFICE.

HUGH WARREN LEE AND JOHN WINDLOW SWINDALE, OF NEWCASTLE-UPON-TYNE, ENGLAND, ASSIGNOR TO SIR W. G. ARMSTRONG, WHITWORTH AND COMPANY, LIMITED, OF NEWCASTLE-UPON-TYNE, ENGLAND.

HOIST.

1,366,394.

Specification of Letters Patent. Patented Jan. 25, 1921.

Application filed September 11, 1919. Serial No. 323,066.

To all whom it may concern:

Be it known that we, HUGH WARREN LEE and JOHN WINDLOW SWINDALE, subjects of the King of Great Britain, residing at 5 Elswick Works, Newcastle-upon-Tyne, England, have invented new and useful Improvements in Hoists, of which the following is a specification.

This invention relates to hoists and especially to those employed for raising projectiles from the shell room of a ship to the working chamber or other desired position. A hoist made in accordance with this invention may obviously be used for many purposes, but it will be described as adapted 15 for use with projectiles.

According to this invention we provide a series of lifting arms to which are imparted reciprocating movements up and down the 20 trunk and rocking movements into and out of the path of the projectiles, and also a series of retaining arms to which are imparted rocking movements into and out of the path of the projectiles.

Preferably each series is duplicated, one 25 being arranged on each side of the center line of the trunk.

When a projectile is delivered on to the lowest pair of lifting arms it is raised by them past the lowest pair of retaining arms which at the moment when the projectile passes has been withdrawn out of the path of the latter and as soon as the projectile has passed the tops of these retaining arms 35 the latter are moved beneath it whereupon the lifting arms are withdrawn from the path of the projectile which is thus left resting on the lowest retaining arms. All the lifting arms then fall and are rocked 40 so that they again come into the path of the projectile. As the lifting arms are raised the second pair picks up the projectile from the lowest retaining arms and lifts it whereupon it is caught and retained by the second 45 pair of retaining arms, and so on. If a second projectile has been delivered to the lowest pair of lifting arms it will have been raised on to the first pair of retaining arms, and so on.

50 Our invention is illustrated by the accompanying drawings, Figure 1 of which is a vertical section through the center line of a

hoist, Fig. 2 is a rear elevation partly in section, Fig. 3 is a vertical section of part of the hoist in a plane at right angles to that of Fig. 1, and Fig. 4 is a horizontal section.

Fig. 1 shows the retaining arms in action and the lifting arms out of action moving downward, while the other figures show the lifting arms almost at the top of their stroke 60 just as they are relinquishing their loads to the retaining arms.

1 is a shaft which can be driven in any convenient way and is provided with a worm 2 meshing with a worm wheel 3 fast on a 65 shaft 4 journaled in a frame 5. Fast with the worm wheel are two plates 6 having in them cam grooves 7 in which work pins 8 on the lower ends of connecting rods 9, the upper ends of which are pivoted to systems 70 of links 10 extending up the rear of the hoist trunk 11. To these systems of links are pivoted equally spaced retaining arms 13, 13, capable of turning on pins 14, 14, carried by the trunk. Fast on the shaft 4 is a pair 75 of cranks 15 on each of which is a pin 16 to which is pivoted the lower end of a rod 17 the upper end of which is pivoted to a frame 18 carrying four horizontal arms 19 which are secured in a pair of sliders 20 80 capable of sliding up and down in guides 21 on the trunk. Fast on each crank pin 16 is a pair of plates 22 each of which has in it a cam groove 23 in which works a pin 24 on a connecting rod 25 the lower end of 85 which is slotted to embrace the crank pin 16, while its upper end is pivoted to a lever arm 26 fulcrumed on a bracket 27 carried by the frame 18. The ends of these arms are pivoted to systems of links 28 similar to 90 the systems 10. To the systems 28 are hinged lifting arms 29 equal in number and equally spaced to the arms 13 and these arms 29 are pivoted at 30, 30, to the sliders 20. 95 31 are inclined guides down which projectiles may be rolled, and 32 is a gate carried by a pillar 33 and urged upward into the path of the projectiles by a spring 34. When this gate is depressed a projectile on the guides 31 rolls down through an aperture 100 35 in the side of the trunk into the path of the lowest pair of lifting arms 29. At the top of the trunk is a heavy door 36 hung on pivots 37 carried by the trunk and capable

of being swung outward by the weight of a projectile so as to let the latter roll out into a waiting tray 38.

The action starting from the position 5 shown in Fig. 1 is as follows:—

The shaft 4 rotates in the direction shown by the arrow, the arms 13 being at first unaffected owing to the fact that the pins 8 are in circular portions of the grooves 7. The 10 cranks 15, however, rotate, drawing down the frame 18 and the sliders 20. The pins 24 are then moved out radially from the axes of the crank pins 16 owing to the shape of the grooves 23, the rods 25 are moved upward 15 relatively to the pins 16, the arms 26 are therefore rocked upward about their pivots and the systems of links 28 are therefore moved upward relatively to the sliders 20, rocking the arms 29 on their pivots and 20 bringing them into their operative positions. As the cranks 15 continue to rotate, the pins 24 enter the circular portions of the grooves 23, after which there is no relative movement between the rods 25 and 17 and therefore none between the systems of rods 28 and the sliders 20 for some time. The frame 18, sliders 21 and arms 29, all rise together carrying up the lifting arms, the lowest 25 pair of which lifts the projectile off the guides 31 and carries it upward; meanwhile the pins 8 fall; the systems of rods 10 therefore also fall, and the retaining arms 13 are rocked inward out of the way of the rising projectile. As, however, the lifting arms 30 reach their highest position the retaining arms are rocked outward again owing to the shape of the grooves, and when the lifting arms begin to fall the projectile is caught up by successive steps from one pair of lifting arms to the next until it reaches the top, 35 whereupon its weight causes the door 36 to open and it falls into the waiting tray 38.

What we claim is:—

1. In a hoist, the combination with a trunk, of a number of retaining arms pivoted to the trunk, a slider movable up and down in the trunk, a number of lifting arms pivoted to the slider, means for rocking the retaining arms on their pivots, positively actuated means for raising and lowering the slider and positively actuated means for rocking the lifting arms on their pivots. 45

2. In a hoist, the combination of a trunk, a shaft, means for rotating the shaft, a cam fast on the shaft, a number of retaining arms pivoted to the trunk, a rod actuated by the cam and adapted to rock the retaining arms on their pivots, a slider capable of movement up and down the trunk, a number of lifting arms pivoted to the slider, positively actuated means for raising and lowering the slider and positively actuated means for rocking the lifting arms on their pivots. 55

3. In a hoist, the combination of a trunk, a shaft, means for rotating the shaft, a cam fast on the shaft, a number of retaining arms pivoted to the trunk, a rod actuated by the cam and adapted to rock the retaining arms on their pivots, a slider capable of movement up and down the trunk, a crank arm fast on the shaft, means actuated by the rotation of the crank arm for moving the slider up and down, a number of lifting arms pivoted to the slider, a cam carried by the crank arm and means actuated by this cam for rocking the lifting arms on their pivots. 60

In testimony that we claim the foregoing as our invention, we have signed our names 70 this 20th day of August, 1919.

HUGH WARREN LEE.
JOHN WINDLOW SWINDALE.
